TELEPHONE SYSTEM

Filed Jan. 2, 1929

Charles R. Brooks

R. S. Richardson Atty.

UNITED STATES PATENT OFFICE

CHARLES R. BROOKS, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed January 2, 1929. Serial No. 329,692.

The present invention relates to telephone systems in general, but is concerned more particularly with telephone systems wherein connections are set up over toll lines and through 5 automatic switching apparatus, and the broad general object may be stated as the provision of new and improved arrangements whereby the association with and the disassociation from a toll line of a switch-controlling device may be made in an efficient manner.

The present invention is concerned more particularly with toll boards built initially for manual toll and service only and which are to be altered to enable automatic switching apparatus to be controlled over the toll lines to set up toll connections.

In certain respects this invention may be considered an improvement on the disclosure in the U. S. patent to Wicks 1,593,737, granted 20 July 22, 1926, with particular reference to the disclosure in Fig. 1 of the patent.

A special feature of the present invention is that responsive to the operation of a simple push button individual to a toll line at 25 an operator's position the calling device at her position is automatically connected in operative relation to the toll line, and when the push button is again operated the calling device is automatically disconnected.

Another feature of the invention is that 30 at a multiple switchboard whereat each toll line appears a plurality of times the operation of a push button individual to a toll line at the second position does not interfere with 35 the connection of a calling device at the first position; the second operator can neither intrude her calling device upon the connection nor cause the first calling device to be disconnected.

Further features of the invention which 40 are mainly subordinate to the foregoing, will appear upon a further perusal of the specification in connection with the accompanying drawing comprising a single sheet.

Referring now to the drawing, two positions, position 1 and position X, of a multi-position toll board are indicated and they are assumed to be the first and last positions, respectively. The connections of the toll 50 lines TL at the toll board are indicated.

At the position X, there is shown a connecting relay 3, and actuating push button P2, an indicating lamp L2, a multiple jack MJ2, an answering lamp AL, and an answering jack AJ. The foregoing equipment is all individual to the toll line TL at the position X. In addition, at the position X there is shown the calling device CD2, this calling device being common to all the toll lines at the position. It will be noted upon inspection that the equipment at position 1 individual to the toll TL is similar to the equipment at position X except that no answering lamp and answering jack are provided, this being in accordance with the standard practice to provide an answering jack at only one position while multiple jacks appear at several positions. The equipment to the right of the dotted line AB is common to the several positions in which the toll line is multipled.

The invention having been described generally, a detailed description of the operation of the apparatus shown will now be given.

Handling an incoming call

It will now be assumed that an incoming call is received over the toll line TL. Connection may be made to the distant end of the toll line TL either manually or automatically as disclosed in the Wicks patent hereinbefore referred to. After the connection is made at the distant end, ringing current is applied at the distant end of the toll line TL and is received at the end of the toll line TL shown in the drawing and is repeated through the windings of the repeating coil and through contacts of the cut-off relay 52 and the associated condenser to the ring-up relay 51 shown in the lower right-hand corner of the drawing. Upon operating, the ring-up relay 51 becomes mechanically locked under the control of the armature of the cut-off relay 52 and it closes a circuit for the answering lamp AL at position X.

When the operator at position X notes the lighted condition of the answering lamp AL she inserts a plug of an idle cord circuit, corresponding to the right hand plug of the cord circuit O in Fig. 1 in the Wicks patent here-

inbefore referred to into the answering jack AJ, whereupon the sleeve relay 4 operates over the sleeve of the plug and jack and at its upper armature closes a circuit through 5 resistance 10 for the cut-off relay 52. Upon the operation of the cut-off relay 51, ring-up relay 52 is removed from in bridge of the tip and ring conductors, and is mechanically unlocked so that it falls back and extinguishes 10 the answering lamp AL.

From this point the connection is handled 75 in the usual manner and as explained in Wicks patent.

15 *Outgoing call from position 1*

It will now be assumed that the operator 20 at position 1 desires to extend an outgoing connection over a toll line such as the toll line TL and that the toll line TL is idle as indicated by the usual tip busy test. The operator accordingly inserts the plug of the cord in use into the multiple jack MJ1 whereupon the sleeve relay 4 operates through the 25 sleeve of the plug and jack and closes a circuit for the cut-off relay 52 by way of resistance 10. At its inner armature, relay 4 places battery through resistance 8 on conductor 11 by way of contacts of relays 3 and 2 as well as similar contacts at intermediate positions. 30 Placing battery on conductor 11 sets up a current flow over the two sides of the toll line TL in parallel, preparing the distant automatic switching apparatus for operation in the usual manner.

35 In order to associate her calling device CD1 with the trunk line TL1, the operator momentarily operates the push button P1, closing a circuit at the upper contacts of the push button through both windings of relay 2 in series, 40 which circuit includes contacts of relays 6 and 4 and also the resistance 9. Upon operating, relay 2 closes a locking circuit through its upper winding alone, by passing the lower winding of the relay so as to lower the potential applied to conductor 11 by way of the 45 resistance 9 from the exchange battery for a purpose to be pointed out more fully hereinafter. At its lower armature, relay 2 prepares a disconnect circuit to be subsequently traced; it prepares a circuit for relay 7 at its upper armature; and at its inner upper armature it disconnects conductor 11 from battery by way of contacts of similar relays in intervening positions, contacts of sleeve 50 relay 4 and resistance 8 and transfers it to battery by way of the impulse springs of the calling device CD1. At the normally-open contacts controlled by the inner upper armature of relay 2, a circuit is closed for the signal lamp L1 by way of conductor 14, contacts of other relays and resistance 8. The lighting of this lamp indicates to the operator that her calling device is connected with this particular toll line.

55 When the operator turns her calling device

CD1 off-normal in the act of dialling the first digit, the off-normal contacts of calling device CD1, the upper contacts thereof, close a circuit through the upper contacts of relay 2, by way of conductor 13, for relay 7. Relay 7 70 operates and locks itself to ground at its upper armature, preparing a circuit for the calling-device-disconnect relay 6 at its lower armature.

75 As the calling device returns to its normal position, the control circuit extending over the two sides of the toll line TL in parallel from battery supplied thereto through the impulse contacts in the calling device CD1 and over conductor 11 by way of the inner 80 upper armature of relay 2 is interrupted a number of times depending upon the digit dialled. The automatic switching apparatus in the distant exchange responds in the manner explained in the Wicks patent referred to. As the operator continues to dial, each of the subsequent digits is transmitted in the manner of the first.

85 As soon as she has dialled the last digit, the operator again pushes the push button P1 momentarily, whereupon a circuit is closed at the lower contacts thereof for relay 6 by way of contacts of relays 2 and 7. Relay 6 operates and closes a locking circuit for itself, opening its initial circuit. At its 90 upper contacts relay 6 removes battery from conductor 12, whereupon relay 2 is released. When relay 2 releases, the control circuit is 95 shifted back to battery through the resistance 8 and the lamp L1 becomes extinguished.

100 The conversation is carried on in the usual manner over the trunk line after the connection has been set up responsive to the trains of impulses sent over the trunk line, and when the connection is to be taken down, the operator withdraws the plug from multiple jack MJ1 whereupon sleeve relay 4 falls back and opens the circuit of relays 6 and 7 at its upper armature, permitting both of these relays to release. The circuit for the cut-off 105 relay is opened at the same time and this relay falls back. At its inner upper armature, relay 4 opens the control circuit over the toll line TL by conductor 11, permitting the connection through the automatic switches in 110 the distant exchange to be released in the usual manner.

Preventing double calling-device connections

115 Assume now that the trunk line TL is in use in the manner hereinbefore described by way of position 1 and that the operator at position X plugs in on the trunk line by way of the multiple jack MJ2, either disregarding or failing to make the usual busy test, and that the operator at position X operates the push button P2 to connect the calling device CD2 with the trunk line TL. In this case, the relay 3 is energized from conductor 12 through both of its windings, but due to the 120

reduced potential on conductor 12, the energization of the relay is not sufficient for its operation. This is because the battery potential from the upper contacts of relay 4 is supplied through resistance 9 and because relay 2 is held operated through the fairly low-resistance upper winding. The potential, however, is sufficient to hold relay 2 operated. The closure of the circuit through the two windings of relay 3 in series does not cause a substantial further lowering of the potential of conductor 12 owing to the fact that the two windings in series have a fairly high resistance. The operator at position X is notified of the failure of the attempt to connect the calling device with the trunk line by the continued unlighted condition of the lamp L2. Since relay 3 is not operated, the lower contacts of the push button P2 are ineffective to cause operation of relay 6, which if it occurred would remove the battery potential from conductor 12 and release relay 2.

After the operator at position 1 has disconnected her calling device CD1 from the toll line by reoperating push button P1, no calling device can intrude upon the connection as disconnect relay 6 maintains battery potential removed from conductor 12 until the connection is taken down.

30 What is claimed is:

1. In a telephone system, a line outgoing from a manual switchboard to an automatic switchboard, a switch-controlling calling device at said manual switchboard common to said line and to other similar lines, a manual circuit-controlling device individual to said line, and means responsive to a momentary operation of said circuit controlling device for operatively associating the calling device with said line and for maintaining said calling device associated with said line after the circuit controlling device has been restored.

2. In a telephone system, a line outgoing from a manual switchboard to an automatic switchboard, a switch-controlling calling device at said manual switchboard common to said line and to other similar lines, a manual circuit-controlling device individual to said line, means responsive to a momentary operation of said circuit controlling device for operatively associating the calling device with said line, and means responsive to the said operation of said circuit controlling device being repeated, after the calling device has been operated to control the switching apparatus at the automatic switchboard, to disassociate said calling device from the line.

3. In a telephone system, a line outgoing from a manual switchboard to an automatic switchboard, a switch-controlling calling device at said manual switchboard common to said line and to other similar lines, a manual circuit-controlling device individual to

said line, means responsive to a momentary operation of said circuit-controlling device for operatively associating the calling device with said line, and means responsive to the said operation of said circuit-controlling device being repeated, after the calling device has been operated to control the switching apparatus at the automatic switchboard, to disassociate said calling device from the line; a signal individual to said line and a circuit for controlling it to indicate when the calling device is associated with said line.

4. In a telephone system, a line outgoing from a manual switchboard, an impulse sender at said manual switchboard common to said line and to a plurality of other lines, an operator's push key individual to said line, means responsive to a momentary operation of said push key for associating said sender with said line, means responsive to an operation of said sender to send impulses over said line for preparing to disassociate said sender and means responsive to a further momentary operation of said push key for bringing about the disassociation of the sender from the line.

5. In a telephone system, a line outgoing from a multi-position manual switchboard, a calling device at each position of said switchboard common to said trunk line and to other similar trunk lines, a manual push key individual to said trunk line at each of said positions, means responsive to a momentary operation of the manual push key at any position for associating the calling device at said position with said trunk line, and means for preventing the momentary operation of the manual push key individual to said line at a second position from associating a second calling device with said trunk line.

6. In a telephone system, a line outgoing from a multi-position manual switchboard, a calling device at each position of said switchboard common to said line and to other similar lines, a manual push key individual to said line at each of said positions, means responsive to a momentary operation of the manual push key at any position for associating the calling device at said position with said line, and means for preventing the disassociation of an associated calling device responsive to the operation of a push key at another position.

7. In a telephone system, a line outgoing from a manual switchboard, means at the manual switchboard for extending a connection to said line, a calling device at said switchboard common to said line and to other similar lines, a manual push key individual to said lines, means responsive to a momentary operation of said manual push key after the said connection has been extended to said line for associating said calling device with said line, means responsive to a further mo-

mentary operation of said push key for dis-
associating said calling device from said line
and for rendering the associating means in-
effective as long as the said connection re-
mains extended to said line.

5 8. In a telephone system, a trunk line out-
going from a multi-position manual switch-
board, a calling device at each position of
said switchboard, a calling device connect-
ing relay individual to said trunk line at
each of said positions, and relay mechanism
common to all of said connecting relays and
arranged to control any one of them.

15 9. In a telephone system, a line outgoing
from a multi-position manual switchboard,
a plurality of calling devices, a plurality of
relays, means for operating any one of said
relays to connect the associated calling device
to the line, and means common to all relays
20 for preventing any other relay from connect-
ing the associated calling device to the line.

25 10. In a telephone system, a line outgoing
from a manual switchboard to an automatic
switchboard, a switch-controlling calling de-
vice at said manual switchboard common to
said line and to other similar lines, a manual
circuit-controlling device individual to said
line, and a self-locking relay responsive to
30 a momentary operation of said circuit con-
trolling device for operatively associating
the calling device with said line.

In witness whereof, I hereunto subscribe
my name this 31st day of December, A. D.
1928.

35 CHARLES R. BROOKS.
